UNITED STATES PATENT OFFICE.

GEORGE E. SERAK, OF CHICAGO, ILLINOIS, ASSIGNOR TO ALFRED DECKER & COHN, INC., OF CHICAGO, ILLINOIS, A CORPORATION OF ILLINOIS.

PATTERN FOR MAKING CLOTHING.

1,394,583.

Specification of Letters Patent.

Patented Oct. 25, 1921.

Application filed November 3, 1919. Serial No. 335,293.

To all whom it may concern:

Be it known that I, GEORGE EDWARD SERAK, a citizen of the United States of America, and a resident of Chicago, Illinois, have invented a certain new and useful Improvement in Patterns for Making Clothing, of which the following is a specification.

This invention relates to patterns for use in making clothing, and more particularly to the patterns employed in tailoring establishments for trousers. These patterns have a center line which must extend parallel with the stripe or design of the fabric, so that the same will extend straight up and down at the front and rear of the trousers when the latter are finished. This is ordinarily accomplished by measuring from the center line of the pattern to a line on the goods or fabric. This of course takes time and is also liable to be inaccurate.

Generally stated, therefore, the object of the invention is to provide a pattern having means or provisions which will obviate the necessity of measuring in the above described manner to ascertain the correct location of the pattern on the goods or fabric, and whereby, at the same time, such means or provisions will not in any way interfere with the use of the pattern in the usual or required manner.

It is also an object to provide certain details of construction tending to increase the general efficiency and the desirability of a pattern of this particular character.

To these and other useful ends the invention consists in matters hereinafter set forth and claimed.

In the accompanying drawings—

Figure 1 is a plan of a pattern embodying the principles of the invention.

Fig. 2 is a similar view.

Fig. 3 is a plan view showing the way in which the pattern shown in Fig. 1 is placed on the goods or fabric.

Fig. 4 is an enlarged detail section on line 4—4 in Fig. 1.

In the manufacture of trousers, one pattern, such as that shown in Fig. 1, is employed in the making of what are called the front leg sections, and another pattern, such as the one shown in Fig. 2, is employed in the making of what are called the rear leg sections. The pattern 1, shown in Fig. 1, is made of any suitable sheet material, such as card-board, and has the desired outline,

and is also provided with a center line 2 where the front crease of the trousers is located. The pattern 2 of Fig. 2 is of similar character, but of different outline, and has the center line 4 where the rear crease 60 of the trousers is located. Pivoted gages 5 and 6, of different lengths, are pivoted on the pattern 1 at 7 and 8, in any suitable manner, and are adapted to be swung into the positions shown in dotted lines. Similar 65 gages 9 and 10 are pivoted on the pattern 3 at 11 and 12, and are adapted to be swung into the positions shown in dotted lines. Thus each gage is adapted to extend evenly 70 on a straight line with a fixed point on the edge of the pattern.

Now assume that the pattern 1 is to be used in making leg sections for trousers in the usual or ordinary manner. In such case, the pattern is laid upon the goods or fabric 75 as shown in Fig. 3, with the center line 2 extending parallel, or as nearly parallel as possible, with the stripe or design or the weave of the cloth. Before marking the cloth, however, the cutter will swing one 80 of the gages 5 and 6 into extended position. The end edge of the gage 5, when the latter is in the fully extended position thereof, is exactly the same distance from the line 2 that the corner 13 is at the other end portion 85 of the pattern, so that a line drawn from the corner 13 to said end edge of the gage 5 will be parallel with the line 2; and in a similar way, the end edge of the gage 6, when the latter is in the extended position 90 thereof, is exactly the same distance from the line 2 that the corner 14 is, so that a line intersecting this corner and the edge of the gage will be parallel with the line 2 at the center of the pattern. Therefore, when the 95 corner 14, for example, and the end edge of the gage 6 are exactly on the same line of the fabric or cloth, it follows that the line 2 is then necessarily parallel with the design or stripe of the cloth. The cutter, in 100 this way, can accurately adjust the pattern on the cloth, in order to bring it into proper position before tracing the outline thereof on the surface of the fabric. This obviates the necessity of measuring from the center line in order to obtain the correct position of the pattern on the fabric, and saves time, and tends to minimize inaccuracy, as it is important, of course, and more especially 105 so in cases where the cloth has a pronounced 110

design or stripe, that the lines of the cloth extend straight up and down parallel with the front and rear creases of the trousers. The positioning of the pattern, of course, 5 may be obtained by the use of either gage, depending upon which is most convenient. After the pattern is properly located on the cloth or fabric, the gage thus employed can then be swung back to its position on the 10 pattern, so that it will not protrude beyond the edge of the pattern, thus allowing the operator or user to trace the outline of the pattern on the cloth in the usual and well known manner. Also, the gages are fold- 15 able over onto the surface of the pattern, so that they will not be in the way when the patterns are stacked and stored away.

As previously stated, the invention relates 20 to patterns in general, and while a pattern for trousers is shown and described, it will be understood that the invention is applicable to patterns for other articles of clothing, and is not limited to patterns of any particular shape size, or character, or for 25 any particular purpose.

The gages assist in positioning the pattern relatively to the weave of the cloth, and obviate the necessity of measuring with 30 tape lines or yard sticks, and greatly facilitate the work.

When each gage is extended, its end edge extends evenly with a fixed point on the edge of the pattern, so that this point and the end of the gage are in line, and such 35 line is parallel with the line 2 or the line 4 of the pattern, as explained, and in this way the placing of the pattern on the cloth (in such a manner that all of said lines will be parallel with the weave or design of 40 the cloth) is made comparatively easy and greatly facilitated.

What I claim as my invention is:—

1. As an article of manufacture, a pattern 45 for use in cutting cloth, said pattern being provided with means for assisting the user in properly positioning the pattern on the cloth, having a longitudinal center line and side edges, the pattern being wider at one end than at the other, and said means compris-

ing one or more gages pivoted on the narrower end portions of the pattern, the length of each gage being such that when extended its outer end is on a line which represents the maximum width of the pattern at one side of said center line. 50

2. The improved pattern of fixed dimensions and shape and having provisions for gaging the position thereof on the cloth, so that the longitudinal center line of the pattern will be parallel with the edge of the 60 cloth, and with the weave thereof, substantially as shown and described.

3. As an article of manufacture, a pattern of fixed dimensions and outline for use in cutting cloth having an irregular 65 edge, said pattern having means extending from said irregular edge to the straight edge of the cloth to insure a proper positioning of the pattern relatively to the weave or design of the cloth. 70

4. As an article of manufacture, a pattern for use in cutting cloth, having an irregular edge or outline, and a gage movably mounted on said pattern to extend therefrom, so that the end of said gage will be 75 in line with a fixed point on the edge of said pattern, and said pattern having a line which is parallel with said line upon which said fixed point and the end of said gage are located, when the gage is extended from 80 the edge of the pattern, thereby to facilitate the placing of the pattern on the cloth in such a manner that both of said lines will be parallel with the weave or design of the cloth. 85

5. A structure as specified in claim 4, said gage being pivoted to swing back upon the pattern to permit the marking of the cloth along the edge of the pattern.

6. A structure as specified in claim 4, in 90 combination with another gage on the opposite side of the pattern, so that the two gages are at opposite sides of said line on the pattern, and one gage being longer than the other, substantially as shown and described. 95

GEORGE E. SERAK.
